WILLIAM L. BARRON, OF NEWARK, NEW JERSEY, ASSIGNOR TO THE SINGER MANUFACTURING COMPANY, A CORPORATION OF NEW JERSEY.

MEANS FOR SECURING BUTTONS TO FABRICS.

1,316,012.

Specification of Letters Patent. Patented Sept. 16, 1919.

Application filed February 20, 1918. Serial No. 218,215.

To all whom it may concern:

Be it known that I, WILLIAM L. BARRON, a citizen of the United States, residing at Newark, in the county of Essex and State 5 of New Jersey, have invented certain new and useful Improvements in Means for Securing Buttons to Fabrics, of which the following is a specification, reference being had therein to the accompanying drawings.

10 Heretofore buttons have been secured to fabrics, garments, etc., by loosely formed stitches around which a thread is wound to form a neck serving to space the button from the body-fabric and protect the fastening 15 stitches against abrasion. It has also been proposed to use a short metal sleeve for the purpose of spacing the button from the body-fabric; the fastening stitches passing within the sleeve. The first of the above 20 mentioned expedients for forming the desired neck is defective for the reason that the winding thread soon becomes worn and breaks or the end thereof becomes loosened and unwinds, much to the annoyance of the 25 wearer of the garment. The metal sleeve expedient is undesirable for the reason that the comparatively sharp edges at the opposite ends of the sleeve are apt to abraid or cut the fastening stitches or the threads 30 of the fabric to which the button is secured. If the fastening stitches are tightly formed, so as to draw the button and metal sleeve tightly together and against the body-fabric, the desired flexibility of the connection 35 between the button and fabric is destroyed and tilting of the button when inserting it in a complementary buttonhole is liable to unduly strain the fastening stitches. If the fastening stitches are not 40 tightly formed the likelihood of the ends of the sleeve to abraid or cut the stitching thread is increased.

Still further, it has been proposed to form 45 a neck integral with the button but this expedient materially increases the cost of the buttons and unduly increases the strain upon the fastening stitches when the button is tilted from side to side in inserting it in a complementary buttonhole. Furthermore, 50 if the neck of the button is made small enough in diameter to be suitable it is easily broken off.

The present invention has for an object 55 to provide an improved, inexpensive and durable necking expedient for use in con-

nection with buttons secured to body-fabrics, garments or the like, whereby the button will be secured in the desired spaced relation to the body-fabric and the fastening stitches protected, and whereby the button 60 may be readily tilted without unduly straining the fastening stitches.

To the above end a small disk of yielding and preferably fibrous material, such as felt or the like through which a sewing needle 65 may be readily passed, is positioned between the button and body-fabric so as to form a non-raveling, non-abrading, yielding and more or less resilient neck for the button affording a maximum of protection for the 70 fastening stitches.

In the accompanying drawings, Figure 1 is a side elevation of the button as secured to a body-fabric or section of a garment. Figs. 2 and 3 are cross-sectional views and 75 Fig. 4 is a disassembled perspective view of the invention.

According to the present invention, in its preferred embodiment, a button 1 having a plurality of centrally disposed sewing eyes 2 is yieldingly held in spaced relation with the body-fabric 3 by means of a disk 4 of yielding, penetrable and preferably resilient material such as felt, leather, rubber or the like and the group of fastening stitches 5 85 which are passed through the eyes 2 of the button, the disk 4 and the body-fabric 3. Although the specific character of the stitches 5 is immaterial, said stitches may, if formed by a machine, comprise a needle-thread and a lower or shuttle-thread interlocked at 6, 6. It will be readily appreciated that the disk 4 forms a yielding neck which holds the button spaced from the fabric and permits the button to be tilted relatively to the fabric, as shown in Fig. 3, without affording a fulcrum about which the button can be tilted as a lever to strain the fastening stitches. Moreover, when the button is tilted, the material of the disk 4 will 90 be compressed, as at 7, Fig. 3, and the penetrative portions of the stitches which are held separated by the yielding wall 8 of material afforded by the disk 4 will assume an easy curve instead of being bent sharply about a corner of hard non-yielding material. When released the button assumes its 95 original position as the compressed edge of the disk recovers its original thickness.

By the use of the present expedient, necks 110

of various heights may be readily formed by providing disks 4 of various thicknesses. Such disks may be made by simply punching them from sheet material and, for this reason, may be cheaply prepared by the garment manufacturer contemplating their use.

The term fabric is used herein in its broadest sense and is intended to include any sort of thin sheet material to which buttons are customarily attached.

Having thus set forth the nature of the invention, what I claim herein is:—

1. As a new article of manufacture, a body-fabric, a button having sewing eyes, fastening stitches passing through the sewing eyes and securing the button to the body-fabric, and a relatively small disk of yielding penetrable material between the sewing eyes and the body-fabric and serving as a neck to space the button from the body-fabric and to protect the fastening stitches against abrasion.

2. As a new article of manufacture, a body-fabric, a button spaced from said body fabric, and means for securing said button in spaced relation to the body fabric, said means including a disk of yielding penetrable material disposed intermediate the button and body fabric, and fastening means extending in a direction normal to the surface of the body-fabric from the button through the disk and into the body-fabric.

3. As a new article of manufacture, a body-fabric, a button spaced from said body-fabric, and means for securing said button in spaced relation to the body-fabric, said means including a separate disk of yielding penetrable material disposed intermediate the button and body-fabric and smaller in size than the button, and fastening stitches 40 passing through the button, the disk and the body-fabric.

4. As a new article of manufacture, a body-fabric, a button having a plurality of sewing eyes, fastening stitches passing 45 through said eyes and into the body-fabric and a relatively small disk of soft material separate from the button and serving to space the button from the body-fabric, a portion of said disk affording a wall between 50 the penetrative portions of said stitches.

5. The combination of a button, a disk of yielding penetrable material separate from and smaller in size than the button, a body-fabric, and fastening stitches, said disk being disposed between said button and body-fabric, and the stitches passing through the button, the disk and body-fabric and serving to hold the parts in their above described relative positions.

In testimony whereof I have signed my name to this specification.

WILLIAM L. BARRON.
